UNITED STATES PATENT OFFICE.

JOHN C. HAMMOND, OF SEATTLE, WASHINGTON.

TOWEL-HOLDER.

1,210,306.

Specification of Letters Patent. Patented Dec. 26, 1916.

Application filed January 21, 1915. Serial No. 3,461.

To all whom it may concern:

Be it known that I, JOHN C. HAMMOND, a citizen of the United States, and a resident of Seattle, in the county of King and State 5 of Washington, have invented certain new and useful Improvements in Towel-Holders, of which the following is a full, true, and exact specification.

My invention relates to towel holders and 10 has for its principal object to provide a simple means for holding towels in bundles, said towels being fitted with eyelets for use on a rod rack, in such a way that they may be placed on the rod rack quickly and easily 15 in the form of bundles, instead of being threaded upon said rack one at a time as is usual.

A further object is to provide a device 20 which in combination with the above mentioned means, forms a simple, convenient and self contained individual safety towel rack and receptacle for the soiled towels.

It will be understood that the laws of 25 many States prohibit the use of other than individual towels in public places, on common carriers, and the like, and further that when such individual towels are furnished in loose bundles, many are misplaced, lost, 30 stolen or used for purposes other than those intended.

To obviate the above mentioned losses and inconveniences, the towels are each fitted 35 with an inserted metal eyelet through which is passed a chain, rod, wire or similar device from which the towel is not separable except when released by the proper attendant who unlocks the securing device.

Other objects will appear as my invention 40 is more fully explained in the following specification, illustrated in the accompanying drawings and pointed out in the appended claim.

In the drawings, Figure 1 is a side elevation 45 of my device, with parts broken away, fitted with a bundle of towels. Fig. 2 is a plan of Fig. 1. Fig. 3 is an enlarged sectional elevation of a part of my device.

Referring more particularly to the drawings, numeral 1 designates a table or stand 50 having a receptacle 2 for soiled towels attached thereto.

3 designates a bundle of towels, each one 55 of which is fitted with an eyelet 3^a, as shown in Fig. 3.

When the towels are laundered, they are 55 placed upon a holder 4 which is cylindrical

in shape, hollow and of such size as to easily pass through the eyelets of the towel. A shoulder 5 on the bottom of holder 4 prevents the towels from slipping from the 60 bottom of said holder. The holder is of such length as to hold a predetermined number of towels and may be filled without the necessity of counting the towels. The bundles of towels are delivered to the customer with the holder 4 in place in the bundle 3 ready for use. A rod or rack 6 of the shape shown in Fig. 1, has its upper end 6^a passed down through the holder 4 until a shoulder 7 on rod 6 brings up against 70 the top of holder 4. The lower end of the rod 6^a below the holder 4, is turned down and threaded as at 8 and is passed through a suitable hole in the top of table 1 and is held thus by a nut 8^a. The lower end 9 of 75 rod 6 may be passed through an empty holder 4^a and set into a bearing 10 at the same time that the upper end is passed through the bundle of towels 3, and when the rod has been secured to the table as previously described, the bearing 10, which is secured to towel receptacle 2, holds the end 9 of the rod 6 so that it cannot be withdrawn from said bearing 10. The towels 80 may be lifted from the bundle 3, one at a 85 time as desired to be used and the eyelet 3^a slips up along the rods 6 into a convenient position for use after which it is slipped down the rod, onto the empty holder 4^a and into the receptacle 2. When the entire bundle 3 has been used, the nut 8^a is removed 90 and the rod released after which the empty holder 4 is removed and a new bundle of towels placed on the table. The holder 4^a, now full of soiled towels, is removed from 95 receptacle and the holder 4 placed on the end 9 of the rod 6, and the rod returned to its proper position, holding the new bundle and secured to the table.

It is thus seen that the towels are held 100 in convenient bundles by holder 4 and that they may be returned to a similar holder in convenient shape for returning to the laundry. Much time and labor and loss of towels is saved by my device.

While I have shown a particular form of embodiment of my invention, I am aware 105 that many minor changes therein, will readily suggest themselves to others skilled in the art without departing from the spirit and scope of the invention, and I therefore, desire to avoid being limited to the exact

form shown and described, except as defined in the appended claim.

Having described my invention, what I claim as new and desire to protect by Letters Patent, is—

In a device for holding soiled and clean towels, the combination of a holder rod bent so as to allow the soiled towel holder to be directly beneath the block of clean towels,
10 whereby both end portions of the rod are straight, parallel and substantially in line vertically, and having a shoulder on the same rod adjacent the upper end of the upper holder, a pair of tubular towel holders, 15 one for each end of the said rod, whereby

clean towels may be held on the upper holder and soiled towels will automatically bunch upon the lower holder, a shoulder on the upper end of said rod and adjacent the lower end of the upper holder, the upper end of the rod being threaded, and a nut adapted to screw onto the said threaded end, whereby the said rod may be rigidly secured to a table through which the said upper end is adapted to pass. 20

JOHN C. HAMMOND.
